REED

Stephen J. Lucas, Chicago, Ill.

Application August 4, 1941, Serial No. 405,389

2 Claims. (Cl. 84—383)

This invention relates to reeds for wood-wind musical instruments and deals particularly with a new and improved reed of different and improved shape from those known in the prior art.

One of the principal objects of this invention is to provide a reed of such design that a standard size reed will include a longer vibrating edge than those heretofore used, with the result that instruments using such a reed may produce better tone and more volume.

Another important object of the invention is to provide a reed in which the side edges of the reed, as well as the end edge, are capable of vibratory movement. Such construction gives more control, permits of longer sustained tone, and makes possible the use of one standard design of reed for each type of musical instrument, irrespective of possible variations in the length of wind opening in the mouthpiece of the individual instrument.

A further object of the invention is to provide a reed having three vibrating edges with a relatively rigid central heart portion extending into the tongue of the reed to provide adequate support for these edges.

Further objects will appear hereinafter.

Referring now more particularly to the drawing in which a saxophone reed has been shown as illustrative of the present invention:

Fig. 1 is a bottom plan view of a reed constructed in accordance with the principles of this invention;

Fig. 2 is a side elevation of the reed illustrated in Fig. 1; and

Fig. 3 is an enlarged detail sectional view taken substantially on the plane of the line 3—3 in Fig. 1.

The reed illustrated in the drawing comprises in general a body portion 10 and a tongue portion 11. These are preferably formed integrally with each other and may be of any of the materials customarily used in the art in the manufacture of reeds of this character, as, for example, wood or any one of the several plastics now commonly used.

The body portion 10 by which the reed may be clamped to the mouthpiece of a musical instrument, is of comparatively great thickness and rigidity, as compared to the tongue portion 11 in order that it may support the tongue portion 11 in proper position with respect to the wind opening in the mouthpiece. As will be seen from an examination of Fig. 1, the body 10 of the reed includes a heart portion 12 extending into the tongue 11 in an acute V-shaped point defined

by the two abrupt angular offset lines 13 and 14 extending diagonally inwardly from the points 15 and 16, respectively, to a vertex at the point 17 located on the longitudinal center line of the reed.

5 This entire heart portion is relatively thick and of comparatively great rigidity in order to give sufficient support to the thin vibrating edges of the tongue surface.

In this connection it will be noted that the 10 tongue surface 11 tapers downwardly from the angular offset 13 to a thin vibrating edge 18 along one side of the reed, while at the opposite side of the reed, the tongue 11 includes a similar but opposite taper between the angular offset 14 and 15 the side vibrating edge 19. These thin side edges 18 and 19 extend between the curved end edge 21 of the reed and the points 15 and 16, and thus, in effect, form one continuous three-sided vibrating edge extending around the three sides of the 20 tongue portion 11. It will be noted, of course, that the tongue portion 11 is tapered not only on each of its sides, but is also tapered between the point 17 and the curved end edge 21.

In operation the heart portion 12 of the reed 25 provides a suitable reinforcement and support for the tongue 11 and thus permits the three vibrating edges 18, 19 and 21 to be formed sufficiently thin to properly perform their function without the sacrifice of the necessary structural strength 30 in the reed. This construction improves the tone and volume of the musical instrument in that it permits vibration of the side edges of the reed, which in the prior art structures known to the applicant, have been formed of relatively heavy 35 non-functioning walls. The flexibility of the side edges of the reed of the present design also provides greater tone control and ease of tonguing, which will permit the entire reed, not under pressure of the ligatures, to vibrate and thus utilize 40 the full tone producing possibilities of the three sides of the mouthpiece opening. This feature, of course, also permits one design of reed to be used in connection with mouthpieces having varying lengths of wind openings, since the thin side 45 edges 18 and 19 will be at least co-extensive with the maximum length of mouthpiece openings. It will also be appreciated that the ease of tonguing of the present design of reed will permit a musician to maintain a longer sustained tone with the same amount of air used on reeds known in the prior art.

While I have shown and described a preferred embodiment of the invention in accordance with the patent statutes, the scope of the invention 55 should not be limited to the precise dimensions

illustrated in the drawing, but should be determined by the language of the following claims.

I claim:

1. A wood-wind reed comprising an elongated body portion and a vibrating tongue portion, said tongue portion having a heart extending lengthwise of the center thereof from the body portion, said heart being relatively thicker and more rigid than the tongue portion and having opposite side edges converging to an apex at the end of said heart extending toward the free end of the vibrating tongue portion, said vibrating tongue portion having the side portions of the top surface thereof on opposite sides of said heart tapering downwardly from said heart to thin opposite edges.
2. A wood-wind reed comprising an elongated

body portion with a vibrating tongue portion at one end thereof, said vibrating tongue portion having a heart extending lengthwise of the center thereof from the body portion toward the free end of the tongue, said heart being thicker and more rigid than the tongue portion and having opposite side edges defined by grooves extending in converging lines to an apex at the end of said heart toward the free end of the vibrating tongue portion, said vibrating tongue having the side portions of the top surface thereof on opposite sides of said heart tapering downwardly from said grooves to thin opposite edges and said tongue portion tapering lengthwise to a thin end edge.
